(57) **CLAIM**

The ornamental design for a scale, as shown and described.

DESCRIPTION

FIG. 1 is a top plan view of a scale of the present invention shown in a “closed” position.

FIG. 2 is a top plan view of the scale shown in FIG. 1 in an “open” position.

FIG. 3 is a side elevation view of the scale as viewed from the left side of FIG. 1, the opposite side being a mirror image thereof.

FIG. 4 is a side elevation view of the scale taken from the left side of FIG. 2, the opposite side being a mirror image thereof.

FIG. 5 is a back elevation view of the scale as seen from the top of FIG. 1 or 2.

FIG. 6 is a front elevation view of the scale as seen from the bottom of FIG. 1 or 2.

FIG. 7 is a bottom plan view of the scale as shown in FIG. 1; and,

FIG. 8 is a bottom plan view of the scale as shown in FIG. 2.
